UNITED STATES PATENT OFFICE.

MILTON O. HAMER, WILLIAM F. LANGE, AND CHARLES C. GRAHAM, OF CRETÉ,
NEBRASKA.

BRUSH.

Application filed February 4, 1922. Serial No. 534,163.

To all whom it may concern:

Be it known that we, MILTON O. HAMER, WILLIAM F. LANGE, and CHARLES C. GRAHAM, citizens of the United States, residing 5 at Crete, in the county of Saline and State of Nebraska, have invented new and useful Improvements in Brushes, of which the following is a specification.

This invention relates to improvements 10 in power driven brushes especially intended for use in cleaning meat blocks, removing paint and for smoothing surfaces, although the invention is useful in various other capacities and for various other purposes.

15 An object of the present invention is the provision of a power operated brush which may be conveniently manipulated by the operator for the purpose of cleaning or smoothing surfaces or articles of different 20 character.

Another object of the invention is the provision of a brush arranged to provide a machine which includes means for catching a 25 sweepings from the brush, the said means embodying a collecting pan mounted so as to permit of sufficient movement to follow the brush over rough or uneven surfaces and thus prevent the escape of the sweepings.

30 Another object of the invention is the provision of a machine of the above character, wherein the parts are so arranged as to provide a compact construction and permit them to be readily disassembled for the removal of the contents of the pan, or for obtaining access to any of the parts of the machine.

Another object of the invention is the provision of a novel brush structure, which 40 permits of the removal of the bristles and the substitution of others, when necessary or desired.

With the above and other objects in view, the invention further includes the following 45 novel features and details of construction, to be hereinafter more fully described, illustrated in the accompanying drawings and pointed out in the appended claims.

In the drawings:

50 Figure 1 is a top plan view of a machine constructed in accordance with the present invention.

Figure 2 is a side elevation of the same.

55 Figure 3 is a top plan view with the cover removed.

Figure 4 is a side elevation with the cover removed.

Figure 5 is a section on the line 5—5 of Figure 3 with the cover in place.

Figure 6 is a similar view on the line 60 6—6 of Figure 3.

Figure 7 is a fragmentary plan view of one end of the cover.

Figure 8 is a similar view showing the latch connection between the collector pan 65 and the frame of the machine.

Figure 9 is a detail longitudinal section through the brush.

Referring in detail to the drawings, wherein like characters of reference denote corresponding parts, the machine as illustrated, 70 comprises a frame 10, which is preferably formed of angle iron so as to provide a flat upper surface.

Mounted in bearings 11 secured to this 75 frame is a shaft 12, which has secured thereon a brush, the latter being designated in its entirety by the reference character 13. It is the purpose of the invention to operate this brush by power and to accomplish this 80 there is provided an electric motor 14, which is secured to a platform 15 located at the end of the machine opposite the brush 13. The shaft of the motor 14 has secured thereon a pinion 16 and this pinion drives a gear 85 17. The latter is secured upon a shaft 18, which is mounted in bearings 19 secured to the frame 10. The end of the shaft opposite the gear 17, has secured thereon a pinion 20 and this pinion engages and drives 90 a gear 21 which is secured to the end of the brush 13. Any suitable means may be employed for supplying current for the operation of the motor 14.

The rear end of the machine is equipped 95 with rigid runners or teeth 22, which are secured to the frame 10 and which extend downwardly and provide a support for the motor end of the machine.

Located within the frame 10 between the 100 platform 15 and the brush 13 is a collector pan 23. This pan includes a bottom, side and rear walls and is open at its top and at the end adjacent the brush 13 and is so positioned that the sweepings from the brush 105 will be directed into this pan. Extending from each side of the pan near the rear end thereof are rearwardly extending lugs 24, which are adapted to be removably received within openings 25 provided in the runners 110

or legs 22, the openings being of a sufficient size to permit of a limited pivotal movement. Extending from one side of the pan 23 and spaced therefrom for passage through a slot 26 provided in the frame 10, is an arm 27. This arm is reduced as shown at 28 so as to provide spaced shoulders 29 and 30. The shoulder 29 is adapted to engage the under side of the horizontal flange of the angle iron of which the frame 10 is formed, while the shoulder 30 is adapted to be engaged by the bill 31 of a hook 32. This hook is provided with a resilient shank 33, which is secured to the frame 10 as shown at 34. The pan 23 will thus be permitted a limited vertical movement at its forward end adjacent the brush, the degree of movement being regulated by the space between the shoulders 29 and 30. As the resilient end of the shank 33 urges the hook inwardly, the latter will normally be positioned in the path of the shoulder 30. By manually moving the hook outward, the arm 27 may be released to permit of the removal of the pan. By pivotally mounting the pan in this manner, the latter will adapt itself to the surface over which the brush is working and any unevenness in this surface will cause the pan to move so as to be always properly positioned to receive the sweepings from the brush. The shoulder 29 is so located as to prevent contact between the pan and brush.

The platform 15 has removably secured thereto a housing 35, which encloses the motor and the gears 16 and 17, this housing being secured in place by means of screws or bolts 36 which pass upward through the platform and engage flanges extending inwardly from the housing. In addition, there is provided a cover 37 which extends over the brush and provides a top or cover for the pan 23. This cover includes a top, side walls and an end wall, the side walls extending downwardly upon opposite sides of the pan 23 and being provided with inwardly extending slotted lugs 38, which engage beneath headed studs 40 which extend upwardly from the frame 10. In addition, the inner end of the cover 37 is provided with spaced lugs 41, which are adapted to be removably received within openings provided in the housing 35. The opposite end of the cover 37 is provided with a transversely extending substantially U-shaped flange 42, which receives the end of the frame 10 and which is provided with openings which register with an opening formed in the said frame. Secured to this end of the cover 37 is a bracket 43 and slidably mounted in this bracket is a bolt 44 which is adapted to engage the openings provided in the flange 42 and the frame 10. This bolt is provided with a finger piece 45 for convenient operation.

Extending downwardly from the frame 10

at opposite ends of the brush 13 are resilient arms or runners 46, the lower ends of these arms or runners are disposed slightly below the periphery of the brush 13 and normally prevent contact of the brush with the surface upon which the machine is resting. A downward pressure on the brush end of the machine will however move the brush into contact with said surface, the degree of contact being regulated by the amount of pressure. By the arrangement of the runners or arms 46, this contact may be nicely regulated. The frame 10 has extending from its rear end a handle or grip 47, while a similar handle or grip 28 extends from the top of the cover 37. This provides convenient means for handling the machine.

In order to prevent the sweepings of the brush from being thrown out between the upper edges of the pan 23 and the adjacent walls of the cover 37, the latter is provided with a transversely and downwardly extending deflector plate 48, while similar plates 49 extend inwardly from the opposite side walls of the pan 23.

In order to adapt the machine for various uses, it is necessary that brushes of different characters be provided. For this purpose the brush is so constructed that the bristles may be removably secured in place. To this end, the brush includes a cylinder 49' which slidably receives within its opposite ends a head 50 having an offset peripheral flange 51. The heads 50 are mounted upon the shaft 12 and are secured in place by means of adjusting nuts 52 and lock nuts 53. Surrounding the cylinder 49' is a spiral brush retaining member 54, whose inner edges are beveled as shown at 55, so that the space between these spirals forms a spiral groove whose walls include oppositely arranged straight portions and oppositely extending inclined portions and define a spiral bristle receiving groove. The bristles which are arranged upon a continuous strip and which are indicated at 56 are adapted to be positioned within the groove and the heads 50 of the cylinder adjusted upon the shaft so as to securely clamp the bristles between the walls of this groove, the inclined portions 55 of these walls serving to effectually retain the bristles in place.

The invention is susceptible of various changes in its form, proportions and minor details of construction and the right is herein reserved to make such changes as properly fall within the scope of the appended claims.

Having described the invention what is claimed is:

1. A machine of the class described comprising a frame, a brush mounted for rotation thereon, means carried by the frame whereby the brush may be rotated, a collecting pan, lugs located at one end of the pan

and removably and freely received within openings provided in the frame and means for removably securing the pan to the frame at a point spaced from the lugs and in a manner to permit of limited pivotal movement with respect to the frame.

2. A machine of the class described comprising a frame, a brush mounted for rotation thereon, means carried by the frame whereby the brush may be rotated, a collecting pan, lugs located at one end of the pan and removably and freely received within openings provided in the frame, an arm carried by the pan for passage through a slot provided in the frame, spaced shoulders formed on the arm and a latch secured to the frame for engagement with one of the shoulders, whereby the pan will be removably secured to the frame in a manner to

permit of limited pivotal movement in opposite directions.

3. A machine of the class described comprising a frame, a brush mounted for rotation in said frame, means whereby the brush may be rotated, a collecting pan secured to the frame adjacent the brush, a cover having one end secured to the frame and extending over the brush and forming a top for the pan and vertically and horizontally disposed deflector plates arranged within the pan along the upper edges thereof and beneath the cover.

In testimony whereof we affix our signatures.

MILTON O. HAMER.
WILLIAM F. LANGE.
CHARLES C. GRAHAM.
